UNITED STATES PATENT OFFICE

CHILLYON MEYER GELLER, OF NEW YORK, N. Y.

DESIGN FOR A DOLL CARRIAGE

Application filed September 26, 1931. Serial No. 41,230. Term of patent 7 years.

To all whom it may concern:

Be it known that I, CHILLYON MEYER GELLER, a citizen of the United States, residing at New York city, in the county of New York and State of New York, have invented a new, original, and ornamental Design for Doll Carriages, of which the following is a specification, reference being had to the accompanying drawings, forming part thereof.

Fig. 1 is a side elevational view of a doll carriage, showing my new design.

Fig. 2 is a plan view.

Fig. 3 is a front elevational view.

Fig. 4 is a rear elevational view of the same.

I claim:

The ornamental design for a doll carriage, as shown.

In testimony whereof I have affixed my signature.

CHILLYON MEYER GELLER.
